UNITED STATES PATENT OFFICE.

ROBERT J. JIMMERSON, OF BROOKLYN, NEW YORK, ASSIGNOR TO LEOPOLD STEINER,
OF NEW YORK, N. Y.

DESIGN FOR A THERAPEUTIC LAMP.

54,630.

Specification for Design.

Patented Mar. 9, 1920.

Application filed July 25, 1919. Serial No. 313,388. Term of patent 7 years.

To all whom it may concern:

Be it known that I, ROBERT J. JIMMERSON, a citizen of the United States, residing at New York city, in the borough of Brooklyn and State of New York, have invented a new, original, and ornamental Design for a Therapeutic Lamp, of which the following is a specification, reference being had to the accompanying drawing, forming part thereof.

The figure is a front elevation of a therapeutic lamp embodying my new design.

Referring to the drawing, particularly to the features which are most prominent, the design consists of a therapeutic lamp having a substantially spherically shaped rear portion A, the bead B, and a substantial frusto-conical front portion C.

I claim:

The ornamental design for a therapeutic lamp as shown and described.

In testimony whereof I have hereunto set my hand and seal this 21 day of July 1919.

ROBERT J. JIMMERSON. [L.S.]
